Patented Aug. 22, 1967

208,388

RING FLANGE FOR PIPE COUPLING

Thomas A. Graham, 1440 Orange Ave.,
San Carlos, Calif. 94070

Filed Jan. 8, 1965, Ser. No. 83,362

Term of patent 14 years

(Cl. D91—3)

FIG. 1

FIG. 2

FIG. 5

FIG. 3

FIG. 4

FIG. 1 is an enlarged inside end view in perspective of a ring flange for pipe coupling showing the features of my new design;

FIG. 2 is an outside end view in perspective of the same;

FIG. 3 is an inside end view in elevation of the same;

FIG. 4 is a side view in elevation of the same; and

FIG. 5 is a fragmentary view in side elevation and in section taken along the line 5-5 of FIG. 3 and showing the configuration of the inside of one attaching ear on my new ring flange design.

I claim:

The ornamental design for a ring flange for pipe coupling, substantially as shown.
